George Cook, *George Cook, Sme*
ATTORNEYS

UNITED STATES PATENT OFFICE

HENRY BAMBERGER, OF NEWARK, NEW JERSEY, ASSIGNOR OF ONE-HALF TO
ALEXANDER MILNE, OF NEWARK, NEW JERSEY.

PHONOGRAPH NEEDLE.

Application filed March 8, 1924. Serial No. 697,798.

To all whom it may concern:

Be it known that I, HENRY BAMBERGER, a citizen of the United States, and a resident of Newark, in the county of Essex and State 5 of New Jersey, have made and invented certain new and useful Improvements in Phonograph Needles, of which the following is a specification.

My invention relates to a phonograph 10 needle and particularly to that class of needle wherein the element which contacts directly with the record is made or composed of a fine wire which may be advanced through a holder as the wire wears.

15 The object of my invention is to provide a phonograph needle having an improved form of holder for the fine wire, so that the latter may be retracted as well as advanced and thus vary the volume of sound being 20 reproduced.

A further object is to provide a phonograph needle having an improved form for the fine wire, the wire being of greater breadth than thickness, and to provide for 25 use therewith a wire holder adapted to engage the wire and prevent it from turning so that the longer axis of a transverse section of the wire will extend in the direction of the length of the grooves of the record to thereby obtain not only greater strength for 30 the fine wire but also to materially improve the quality of the reproduced sound.

With the foregoing and other objects in view, my invention consists in the improved 35 phonograph needle illustrated in the accompanying drawing and hereinafter described and claimed, and in such variations and modifications thereof as will be obvious to those skilled in the art to which my invention relates, it being understood that changes 40 may be made within the scope of what is claimed without departing from the spirit thereof.

The preferred embodiment of my invention 45 is disclosed in the accompanying drawing, wherein:

Figure 1 is a plan view of a partially 50 formed phonograph needle embodying the characteristic features of my invention;

Figure 2 is a plan view of the complete 55 needle;

Figure 3 is a view in transverse section taken on the line 3—3 of Figure 2;

Figure 4 is a similar view taken on the 55 line 4—4 of Figure 2;

Figure 5 is a view in elevation and partially in section of my improved needle in use, with the wire extended so as to act as a so-called "soft" needle;

Figure 6 illustrates my needle as being 60 used as a so-called "medium" needle;

Figure 7 is a similar view illustrating it acting as a so-called "loud" needle;

Figures 8, 9, 10 and 11 are sectional views 65 of wires of various contour, each, however, having the characteristic that one transverse axis is considerably longer than the other transverse axis;

Figure 12 is a diagrammatic view of the wear of the ordinary solid needle; and 70

Figures 13, 14 and 15 are diagrammatic views of the manner of wear of the wire of my improved needle.

Referring specifically to the several views, 75 wherein similar reference numerals designate corresponding parts throughout, the wire holder of the needle is cut or stamped to the configuration illustrated in Figure 1 and while in this shape is composed of the head pieces 20, 21, connected by an intermediate bar 22.

The head piece 21 is provided with a threaded opening 23, while the head piece 20 is provided with a corresponding opening 24, the latter being reamed out, however, for clearance for a screw which 80 engages the threaded opening 23, as will later appear. The head 21 and portion of the connecting bar 22 are provided with a longitudinally extending groove or channel 25, the same being of relatively greater 85 thickness than breadth and communicating with the groove or channel is an opening 26 extending through the bar. The bar is then bent about a transverse axis, bringing the head pieces 23—24 together, the same being 90 held in such position by the thumb screw 27. The parts as thus arranged form a wire 95 holder, and the bar 22 now forms a shank 28 which is adapted to fit within the needle-receiving socket of a phonograph reproducer, as clearly illustrated in Figure 5. The opening 26 now occurs at the extremity of the shank 28 and provides for the insertion of a sound reproducing wire 29, the same extending not only through the opening 26 but also along and through the channel or groove 25. The wire 29 is of slightly greater thickness than the depth of the groove 25, so that as the thumb screw 27 is 100 turned the wire will be pinched between the 105

110

two head pieces 20—21 and accordingly clamped in place. The wire at its front extremity will protrude beyond the wire holder, as illustrated at 30 in Figure 2, and this 5 protrusion can be regulated by exerting a pressure upon the rearwardly protruding extremity of the wire, so that the wire may be either advanced or retracted, and, as 10 illustrated in Figures 5, 6 and 7, will impart to the needle the characteristic known as "soft", "medium" or "loud", respectively.

As illustrated in Figures 8, 9, 10 and 11, the wire may partake of several different cross-sectional forms, it being noted, however, that in all cases the wire is of greater 15 breadth than thickness, and I have found that a wire which is approximately .006" in width and .011" in breadth gives very excellent reproduction.

20 Referring particularly to Figure 8, the needle is composed of a substantially circular body 31, from diametric portions of which extend the ribs 32. In Figure 9 the wire partakes of an oval cross section. In 25 Figure 10 the wire partakes of a rectangular cross section, with the smaller sides slightly convexed, and this particular form I have found provides a very sturdy wire and at the same time gives a very excellent reproduction. In Figure 11 the wire is shown to 30 be of substantially diamond-shape cross section.

My improved wire holder is provided with 35 irregular or knurled surfaces 33 so as to facilitate the handling of the needle. I would particularly call attention to the diagram illustrated in Figure 12, wherein the usual ordinary form of solid needle is illustrated and the distance "A" represents the contact 40 of the point of the needle with the record after the playing of a single record. The distance "A," it is to be noted, is a diameter, and it is the large size of this dimension that causes the scratchy noise and poor 45 reproduction. The manner in which my improved needle overcomes these faults is clearly illustrated in Figures 13, 14 and 15, the diagram 13 illustrating the wire prior to any wear whatever, it being noted that the 50 side presented to view is the larger diameter, i. e., the .011".

After a considerable number of records have been played with my improved needle, the point wears along the diagonal line B, 55 and before this diagonal line extends entirely across the end of the needle, the entire holder is reversed or turned through 180°, which turns the wire into position as illustrated in Figure 15, causing the needle to 60 then wear along the line C. This wear is

allowed to take place until the line C passes the longitudinal axis D of the wire, whereupon the holder will again be reversed and the action repeated. In this manner, the surface exposed to the record is maintained 65 at a minimum and a very excellent quality or tone of the reproduced sound will accordingly be had.

Having thus described and explained my invention, I claim and desire to secure by 70 Letters Patent:

1. A phonograph needle holder formed of a single piece of metal including two head pieces and a connecting shank, one head piece and one-half of the shank provided 75 with a groove and with an opening extending through said shank communicating with said groove, said shank being bent about its center to form a filler sleeve to fit the ordinary stylus socket and to bring the two heads together and means for clamping the two head pieces together to clamp a wire within said groove.

2. A phonograph needle holder formed of a single piece of metal including two 85 head pieces and a connecting shank, one head piece and one-half of the shank provided with a groove of relatively greater width than depth and with an opening extending through said shank communicating 90 with said groove, said shank being bent about its center to form a filler sleeve to fit the ordinary stylus socket and to bring the two heads together, and means for clamping the two head pieces together to clamp a wire 95 within said groove.

3. A phonograph needle holder formed of a single piece of metal including two head pieces and a connecting shank, one head piece and one-half of the shank provided 100 with a groove and adapted to hold a wire of approximately eleven one-thousandths of an inch in breadth and six one-thousandths of an inch in thickness, and with an opening extending through said shank communicating 105 with said groove, said shank being bent about its center to form a filler sleeve to fit the ordinary stylus socket and to bring the two heads together, and means for clamping the two head pieces together to clamp a wire 110 within said groove.

Signed at New York, borough of Manhattan, in the county of New York and State of New York, this 6th day of March, A. D. 1924.

HENRY BAMBERGER.
